Fig. 1.

Fig. 2.

Fig. 3.

FIG. 1 is a front elevational view of the ophthalmic spectacles embodying my new design.

FIG. 2 is a perspective front view thereof.

FIG. 3 is an enlarged cross-sectional view thereof taken on line 3—3 of FIG. 1, the left lens and temple being omitted for convenience of illustration.

The characteristic features of my design reside in the specific configuration of the frame front, which consists of the rectilinear front bar and the lens-supporting members secured behind the front bar.

I claim:

The ornamental design for ophthalmic spectacles, as shown and described.
